US00D435650S

United States Patent

[19]

Kwok

[11] Patent Number: Des. 435,650

[45] Date of Patent: ** Dec. 26, 2000

[54] **COMBINED NASAL MASK SHELL AND CUSHION**

[75] Inventor: **Philip R. Kwok**, West Pymble, Australia

[73] Assignee: **ResMed Limited**, North Ryde, Australia

[**] Term: **14 Years**

[21] Appl. No.: **29/075,798**

[22] Filed: **Aug. 25, 1997**

[30] **Foreign Application Priority Data**

Feb. 25, 1997 [AU] Australia 579/97

[51] **LOC (7) Cl.** **29-02**

[52] **U.S. Cl.** **D24/110.1; D24/110.4**

[58] **Field of Search** D24/110.1, 110.4, D24/110.5; 128/207.13, 207.12, 207.18, 206.28, 206.24, 206.26, 206.11, 206.12, 205.25, 206.21, 207.11, 207.17, 206.18

[57] **CLAIM**

The ornamental design for a combined nasal mask shell and cushion, as shown and described.

DESCRIPTION

FIG. 1 is a perspective view of a combined nasal mask shell and cushion of the present invention.

FIG. 2 is a front view of a combined nasal mask shell and cushion of the present invention.

FIG. 3 is a right side view of a combined nasal mask shell and cushion of the present invention, the left side view being a mirror image thereto.

FIG. 4 is a top plan view of a combined nasal mask shell and cushion of the present invention.

FIG. 5 is a bottom plan view of a combined nasal mask shell and cushion of the present invention.

FIG. 6 is a rear view of a combined nasal mask shell and cushion of the present invention.

FIG. 7 is a perspective view of a second embodiment of a combined nasal mask shell and cushion of the present invention.

FIG. 8 is a front view of a second embodiment of a combined nasal mask shell and cushion of the present invention.

FIG. 9 is a right side view of a second embodiment of a combined nasal mask shell and cushion of the present invention, the left side view being a mirror image thereto.

FIG. 10 is a top plan view of a second embodiment of a combined nasal mask shell and cushion of the present invention.

FIG. 11 is a bottom plan view of a second embodiment of a combined nasal mask shell and cushion of the present invention; and,

FIG. 12 is a rear view of a second embodiment of a combined nasal mask shell and cushion of the present invention.

1 Claim, 4 Drawing Sheets
